UNITED STATES PATENT OFFICE.

JAMES EMBLETON, OF COLUMBUS, OHIO, ASSIGNOR TO J. F. ANGELL, OF COLUMBUS, OHIO.

MIXING-MACHINE.

SPECIFICATION forming part of Letters Patent No. 787,441, dated April 18, 1905.

Application filed November 7, 1904. Serial No. 231,710.

To all whom it may concern:

Be it known that I, JAMES EMBLETON, a citizen of the United States, residing at Columbus, in the county of Franklin and State of Ohio, have invented a certain new and useful Improvement in Mixing-Machines, of which the following is a specification.

My invention relates to a new and useful improvement in mixers, and more particularly to that class known as "concrete-mixers."

The object of the invention is to provide simple and effective means for feeding the materials to be mixed proportionately into a mixing-drum.

Another feature lies in a revolving mixing-drum having a delivery-spout and provided with fixed mixing-vanes and a self-cleaning mixing paddle-wheel.

Finally, the object of the invention is to provide a device of the character described that will be strong, durable, and efficient and one in which the several parts will not be liable to get out of working order.

With the above and other objects in view the invention consists of the novel details of construction and operation, a preferable embodiment of which is described in the specification and illustrated in the accompanying drawings, in which—

Figure 1 is a side elevation showing the mixing-drum broken away to illustrate the interior construction thereof. Fig. 2 is a plan view showing a portion of the mixing-drum and the hopper broken away to illustrate the conveyers and their supports. Fig. 3 is an end elevation of the delivery end of the mixer, and Fig. 4 is an end elevation of the feed end.

In the drawings, the numeral 1 designates the sills or beams upon which the machine is mounted. Supported from the sills by suitable chairs or brackets 2 is a vertically-extending hopper 3, having a central longitudinal partition 4, which divides it into a cement-compartment 5 and a sand and gravel compartment 6. Arranged in the bottom of each compartment is a spiral conveyer 7, which are rotatably supported upon the bearing-bar 8 at one end and the front wall

of the hopper at the other end. The shafts of the conveyers project beyond the front wall of the hopper and carry the intermeshing driving-gears 9 and 10. The gear 10 is mounted upon the shaft of the sand and gravel conveyer and is somewhat smaller than the gear 9, mounted on the cement-conveyer. It is obvious that by such an arrangement the sand and gravel conveyer will revolve at a higher rate of speed than the cement-conveyer. The sand and gravel conveyer also carries a sprocket-wheel 11, which is connected, by means of a chain 12, to the sprocket 13, keyed upon the longitudinal drive-shaft 14, which will be hereinafter described. The hopper communicates with a delivery and bearing collar 15, which projects concentrically in the annular inwardly-projecting flange 16 of the mixing-drum 17. The drum 17 is arranged on its inner periphery with a plurality of inclined angular vanes 18, which are adapted to thoroughly mix the materials received from the hopper when the drum 17 is rotated. A flaring delivery-spout 19 is mounted upon the outer open end of the drum 17 and is provided with the paddle-wheel 20. The paddle-wheel 20 is loosely disposed within the spout and comprises rearwardly-inclined paddles or blades 21 and the open-ring hubs 22, from which the said blades 21 are supported. The paddle-wheel 20 has a diameter slightly less than the inner diameter of the spout and is held in position by the inwardly-projecting lugs 23 and 24. The lugs 24 are disposed at the mouth of the spout and are formed with lateral projections or flanges 25, against which the blades 21 abut, thus preventing the wheel from sliding forward out of the spout. The lugs are positioned with the flanges 25 projecting in opposite directions. The mixing-drum and therefore the spout are caused to revolve in the direction of the arrow A, (shown in Fig. 3,) and it will therefore be seen that the blades of the paddle-wheel are impinged by the lugs 23 and 24, and thus caused to turn therewith. It is obvious, however, that by grasping the paddle-wheel and giving it a slight turn in the opposite direction it may be disengaged from the said lugs and removed from the

spout. The mixing-drum and spout are revolved at a comparatively low rate of speed, and the paddle-wheel 20, being of smaller diameter than the spout, will drop by gravity whenever the lugs 23 and 24 upon each side of the spout stand in vertical relation, which, as is obvious, will occur twice during each revolution of the mixing-drum. The paddle-wheel hangs close to the lower inner periphery of the spout until that portion resting on the periphery is carried above a line passing horizontally across the center of the spout, when its own weight will cause it to drop or slide or begin to drop or slide downwardly until its opposite side rests upon the lower inner periphery. The falling of the paddle-wheel will jar it, and thus cause the concrete to drop from the blades and parts of the wheel. By this means the wheel is self-cleaning and will therefore produce better results. A water-pipe 26 projects through the outer ring 22 of the paddle-wheel within the said wheel, terminating short of the inner ring 22 and is provided with perforations or suitable openings through which a suitable amount of water is delivered upon the mixture.

The mixing-drum is formed at each end with flanged circular tracks 27, secured upon its outer periphery, which tracks rest upon friction driving-wheels 28, supported upon each side of the drum upon the shafts 14 and 14^a. For insuring a positive drive of the mixing-drum I form the forward track 27 with a ring gear 29, which meshes with a driving-pinion 30, keyed upon the shaft 14 in juxtaposition to one of the forward friction-wheels 28. It is obvious that the mixing-drum is supported upon the friction-wheels and is held against longitudinal displacement by the flanged tracks 27.

The shaft 14 is rotatably supported upon the standards 31, mounted upon the sills 1. For the purpose of driving the shaft 14 and imparting motion to the various parts of the mixer I mount upon the said shaft a worm-gear 32, meshing with which is disposed the transverse worm 33, securely supported upon a shaft journaled in the brackets 34 and carrying the band-wheels 35 and 36, the former loosely mounted and the latter keyed to the said shaft for the purpose of driving the same.

Over the gears 9 and 10 and the sprocket-wheel 14 I mount upon the hopper 3 a downwardly-inclined shield 37, which protects the same from falling gravel, cement, sand and the like.

In operation, power having been applied to the band-wheel 36 and the shaft 14 caused to revolve by the worms 32 and 33, motion is transmitted to the drum 17 through the wheels 28 and the pinion 30 and to the conveyors 7 by the sprocket-wheel 13, chain 12, sprocket-wheel 11, and gears 9 and 10, the conveyors, as hereinbefore described, being

revolved at different rates of speed. Cement is delivered into the compartment 5, and the material with which it is to be mixed—such as sand, gravel, &c.—is delivered into the compartment 6. The conveyer in the compartment 6 revolving at a higher rate of speed than the conveyer in the compartment 5 will thus deliver a greater amount of sand and gravel through the collar 15 than the amount of cement conveyed or delivered by the said conveyer in the compartment 5. The materials delivered through the collar 15 pass into the mixing-drum 17, which, as before stated, is revolved at a comparatively low rate of speed. The vanes 18 of the said drum catch up the materials and thoroughly mix them and owing to their forwardly-inclined arrangement gradually move the materials toward the spout 19 as they are mixed. Materials passing into the spout 19 are thoroughly mixed with water, delivered from the pipe 26 by means of the paddle-wheel 20, which is caused to revolve with the said spout. It is to be observed that the materials are maintained in a dry state until they are delivered into the spout 19, where they are mixed with water from the pipe 26. It is therefore obvious that some means for cleaning the paddle-wheel 20 must be provided or else the mixture would adhere thereto and interfere with the successful operation thereof. As before described, the paddle-wheel is self-cleaning, and owing to its falling or jarring action the materials are removed by the vibration caused by the jarring of said paddle-wheel when it falls twice during each revolution.

Having now fully described my invention, what I claim, and desire to secure by Letters Patent, is—

1. In a mixing-machine, the combination with feed-troughs having feeding devices, and means for driving the feeding devices, of a mixing-drum having internally-arranged mixing devices, a delivery-spout carried by the drum, jarring mixing means arranged within the spout, and means for imparting motion to the parts.

2. In a mixing-machine, the combination with feeding means, of a revolving mixing-drum having forwardly-inclined mixing devices arranged upon its inner periphery, a flaring delivery-spout carried upon the drum and movable therewith, a mixing-wheel fitting loosely in the spout, means projecting from the spout and engaging the mixing-wheel to cause the same to turn with the spout, means for introducing water into the spout, and means for imparting motion to the drum.

JAMES EMBLETON.
